UNITED STATES PATENT OFFICE.

VINCENT LINK, OF DETROIT, MICHIGAN, ASSIGNOR TO THE STUDEBAKER CORPORATION, OF SOUTH BEND, INDIANA, A CORPORATION OF NEW JERSEY.

INTERNAL-COMBUSTION ENGINE.

Application filed December 27, 1923. Serial No. 683,054.

This invention relates in general to internal combustion engines and particularly to cam followers and their use in connection with the rocker arms, valve tappets and the like, used in the valve operating mechanism of the engines.

An object of this invention is to provide a cam follower which will automatically adjust itself to bear with the full length of its contact face against the cam, regardless of whether or not the line of contact between the cam follower and the cam is at all times in a plane parallel to the axis of the cam shaft.

Another object is to provide a cam follower of the non-rotating type having a sliding seat in its support and means for allowing it to slidably move on this seat.

Still another object is to provide such a cam follower that will be simple in construction, efficient in operation and economical to produce.

The above and further objects will be apparent from the following explanation and description, reference being made to the accompanying drawings which show one embodiment of the present invention.

In the drawings in which like numerals refer to like parts throughout the several views:

Figure 1 is a fragmentary transverse sectional view of an internal combustion engine in connection with which I show an embodiment of my present invention.

Figure 2 is a side view of a rocker arm in which my present invention is incorporated.

Figure 3 is a fragmentary sectional view, taken on a plane parallel to the drawing centrally through the cam engaging portion of the rocker arm of Figure 2, the cam follower member being removed to more clearly show the construction.

Figure 4 is a side view of the cam follower member.

Figure 5 is a fragmentary sectional view taken on the line 5-5 of Figure 2.

Figure 1 shows an internal combustion engine having a crank-case 10 which supports a cylinder block 11 which in turn is covered by the cylinder head 12. The cylinder block 11 is provided with a cylinder having a liner 13 in which a piston 14, connected to the crank shaft 15 by the connecting rod 16, reciprocates. The combustion chamber 17 is connected by the passage 18 to

either an intake or exhaust manifold as the case may be, the entrance of combustible mixture to, or the emission of exhaust gas from, the combustion chamber 17 being controlled by the poppet valve 19 of conventional construction. The valve 19 is operated by a cam 20 on a shaft 21 through the medium of a rocker arm 22. The rocker arm 22 is pivotally supported on the crank case 10 at 23 and is provided with a screw 24 which is adapted to adjustably engage the lower end of the poppet valve 19, the screw 24 being locked in adjusted position by the lock nut 25. It is also provided with a cam follower member 26 which is adapted to engage the cam 20, and the movement that the cam imparts thereto is transmitted through the arm and screw 24 to the valve 19 and thus controls the position thereof.

In the conventional constructions used today in internal combustion engines, whether the valve be operated directly by the cam, or through the medium of a valve tappet or rocker arm, no provision is made to allow the contact face of the cam follower to adjust itself to any angularity or unevenness of the cam. In the conventional valve tappet of the mushroom construction the axis of the tappet is designed to be perpendicular to the axis of the cam shaft, the contact face of the tappet being perpendicular to the axis of the tappet and all longitudinal lines of the cam are parallel to the axis of the cam shaft. This design if correctly carried out in the manufacture provides a full length line of contact between the cam and the valve tappet. However, due to manufacturing difficulties commonly arising in production, it has been found practically impossible to consistently obtain these conditions accurately enough to insure an absolutely correct full line of contact between the cam and valve tappet or follower face. The axis of the tappet guide may be slightly out of perpendicular to the axis of the cam shaft, the plane of the tappet face may not be absolutely perpendicular to the axis of the tappet, or the longitudinal lines of the cam may not be parallel to the axis of the cam shaft. Any one of these conditions may be such as to prevent the cam and tappet from contacting to the full degree, and any one of them will usually allow but a point of contact between the two, which obviously is an undesirable con-

dition and one that leads to shorter life of the parts and may cause improper functioning of the engine of which they are a part.

6. The same thing is true when a roller type follower is used in place of the mushroom type, or in fact in any construction that is now conventional practice.

The present invention, as has been stated, 10 has for its object the providing of means whereby a full line of contact will be provided between the cam and follower regardless of any manufacturing irregularities of the parts involved. The means I show in 15 the drawings are as follows:—The cam follower 26 is provided with two parallel faces 27 and 28 (Figure 4) which are adapted to be closely but slidably received, between the two parallel faces 29 of the recess 30 20 in the rocker arm 22. Its contact face is rounded off as at 31 about a line which is substantially parallel to the axis of the cam shaft 21 when the two are placed in operative position. This is to provide that the 25 line of force transmitted from the cam 20 through the follower 26 will always pass centrally therethrough and will not, in effect, change the ratio of cam lift to valve lift, and also will not tend to bind the follower 30 on the surfaces 29 of the recess 30.

The rear face of the follower 26 is rounded off as at 32 about a line perpendicular to the faces 27 and 28, and to the axis of the cam shaft 21, to the form of a cylindrical surface, and the bottom of the recess 30 is formed as at 33 to match it and form a seat therefor. This construction is such as to allow the follower 26 to slide on the seat 33 and adjust itself to bear against the cam 20 40 for its full width, thus compensating for any irregularities in the manufacture of the parts involved. In order to prevent the follower 26 from dropping out of the arm 22 and yet allow it sufficient latitude of 45 movement to adjust itself as described, I provide a pin 34 secured in the opening 35 of the arm 22 and also provide in the cam follower 26 for the passage of the pin 34, an opening 36 which is considerably larger 50 in diameter than the pin 34, in order to allow movement of the follower 26. The opening 36 is of necessity larger than the pin 34 in order to allow the movement described inasmuch as the construction is such 55 as to make it undesirable to have the axis of the cylindrically shaped surfaces 32 and 33 within the follower 26. The opening 36 as shown is considered sufficiently large to allow for any possible variations in the fol- 60 lower 26, but it is to be understood this detail may be varied to suit any conditions that may arise.

It is evident from the foregoing that I have provided a cam follower that, because 65 of its ability to angularly adjust itself, will

consistently provide a full line of contact between itself and the cam surface, regardless of the prevailing irregularities experienced in manufacturing.

What I claim is:—

1. In a device of the class described, a rocker arm having a curved seat, a cam follower having a curved outer face mating with said curved seat to permit oscillatory movement of said cam follower, and means to prevent disengagement of said rocker arm and cam follower. 70

2. In combination with a cam and a member operated thereby, of a cam follower having an external cylindrical face engaging in a cylindrical seat in said member to permit oscillatory movement of said cam follower in a plane parallel to the axis of said cam. 80

3. In combination, a valve, a cam, a cam follower, and a member for supporting said cam follower and transmitting motion therefrom to said valve, said member having a cylindrical seat contacting with an outer cylindrical surface on said cam follower to 85 permit oscillatory movement to said follower. 90

4. In combination with a cam, a cam follower provided with a cylindrical external seat upon which it is adapted to oscillate 95 in a plane parallel to the axis of said cam.

5. In combination with a cam, a cam follower, and a supporting member for said cam follower, said cam follower being adapted to have sliding contact with said 100 cam and being provided with an exterior cylindrical face to engage a cylindrical seat in said supporting member.

6. In combination, a cam, a valve, a rocker arm to operate said valve, and a cam follower supported by said rocker arm and operated by said cam, said cam follower having a cylindrical outer surface engaging a cylindrical seat in said rocker arm to provide oscillatory movement of said follower in a 110 direction parallel with the axis of said cam, and means to prevent disengagement of said follower with said rocker arm. 105

7. In combination with a cam, a cam follower, and a cam follower supporting member, said cam follower supporting member being provided with a recess for receiving said cam follower which has two flat faces in a plane parallel to the axis of said cam and a cylindrical seat perpendicular to said 115 flat faces, said cam follower being provided with a cylindrical face to engage the cylindrical seat of said recess. 120

8. In an internal combustion engine, a cam shaft having a cam thereon, a valve, a rocker arm provided with a recess having two parallel side walls and a curved wall pivoted to said engine to operate said valve, and a cam follower operated by said cam provided with parallel side walls and a 125 130

curved outer face mounted in said recess, said curved surfaces co-operating to provide oscillatory movement of said follower relative to said cam, and means to prevent disengagement of said follower with said rocker arm.

9. A valve tappet, comprising a tappet body and a separate tappet head swiveled thereto on a line running crosswise of an associated cam shaft, whereby the head may adjust itself to engage the cam squarely across its face.

10. A valve tappet, comprising a tappet body and a separate tappet head movable relative to the body in a plane parallel to the axis of an associated cam shaft, whereby the head may adjust itself to engage an associated cam squarely across the face of the cam.

11. A valve tappet, comprising a tappet

body and a separate tappet head fulcrumed thereon on a line running crosswise of an associated cam shaft, whereby said head may adjust itself to engage an associated cam squarely across its face thereof.

12. A valve tappet, comprising a tappet body, a separate tappet head, and a pivot pin connecting said body and head, said pivot pin extending crosswise of an associated cam shaft.

13. A valve tappet, comprising a tappet body forked at its lower end, a tappet head having an ear located between said forks, and a pivot pin extending through said forks and ear, said pin extending crosswise of an associated cam shaft.

Signed by me at Detroit, Michigan, U. S. A., this 19th day of December, 1923.

VINCENT LINK.
